CLAIM

The ornamental design for a handheld cleaning appliance as shown and described.

DESCRIPTION

The patent or application file contains at least one drawing executed in color. Copies of this patent or patent application publication with color drawing(s) will be provided by the Office upon request and payment of the necessary fee.

1.1 is a front view of a first embodiment of a handheld cleaning appliance, showing the new design;

1.2 is a back view thereof;

1.3 is a left view thereof;

1.4 is a right view thereof;

1.5 is a top view thereof;

1.6 is an enlarged top view thereof;

1.7 is a bottom view thereof;

1.8 is an enlarged bottom view thereof;

1.9 is a front, top perspective view thereof;

1.10 is a front, bottom perspective view thereof;

1.11 is a front, left perspective view thereof;

2.1 is a front view of a second embodiment of a handheld cleaning appliance, showing the new design;

2.2 is a back view thereof;

(Continued)

2.3 is a left view thereof;
2.4 is a right view thereof;
2.5 is a top view thereof;
2.6 is an enlarged top view thereof;
2.7 is a bottom view thereof;
2.8 is an enlarged bottom view thereof;
2.9 is a front, top perspective view thereof;
2.10 is a right, bottom perspective view thereof; and
2.11 is a front, left perspective view thereof.
 The portions of the first and second handheld cleaning appliances shown by coloring with yellow in the reproductions form no part of the claimed design.
